BRAKE HANGER RETAINER

Malcolm S. Johnson, Chicago, Ill., assignor to
 Illinois Railway Equipment Company, Chicago,
 Ill., a corporation of Illinois

Application May 6, 1944, Serial No. 534,467

13 Claims. (Cl. 188—209)

My invention relates to means for retaining brake hangers, more especially, the upper ends of the standard link type of brake hangers in the hanger brackets secured to the railroad car truck and at the same time relieve the hanger brackets (which generally are formed integral with the truck frame members) of wear resulting from the more or less constant vertical and lateral vibratory movements of the hangers.

The invention has for its object the provision of hanger retaining means, consisting of a pair of complementary hanger receiving members or blocks arranged in superposed relation, with the upper end of the brake hanger therebetween and adapted to effect interlocking relation with each other against vertical separation and against independent horizontal movement and hence eliminates undue wear of the bracket and of the usual retaining pin or key and prevents the latter working loose in the hanger bracket.

Another object of the invention is the provision of retainer members that are interchangeable, which permits the combined retainer to be reversed or one section or member to be renewed without the necessity of replacing the entire retainer.

A further object of the invention is a retainer which provides proper lateral clearance at the sides of the hanger to permit sufficient tilting without increasing its vertical clearance, to compensate for the lateral movements of the brake head, thereby eliminating the usual wear encountered on the brake head resulting from the crowding of the brake shoe by the wheel flange.

The foregoing enumerated objects and advantages, as well as other advantages inherent in the invention, will all be readily comprehended from the following detailed description of the accompanying drawing wherein:

Figure 1 is a side elevation of the hanger bracket provided with my improved retainer and the upper portion of the brake hanger; the truck frame being broken away.

Figure 2 is a view taken at right angles to Figure 1 and looking at the forward side of the bracket and my improved retainer.

Figure 3 is a perspective view of the two retainer members in spaced relation one above the other.

Figure 4 is a vertical sectional view taken substantially on the line 4—4 of Figure 1, looking in the direction of the arrows and showing the hanger in normal position.

Figure 5 is a similar view showing the hanger tilted toward one side; while the tilt of the hanger toward the opposite side of the vertical median line is shown in dotted lines.

My improved retainer is especially intended for use with the continuous link or A. A. R.

standard type of brake hanger, the upper end whereof is shown at 10 (which may be substantially circular cross section), and is adapted to pendently support the hanger in the open sided bracket 11, secured to the truck side frame adjacent the wheel ends thereof.

The retainer consists of a pair of members or blocks 12, 12 identical in construction, adapted to be employed in superposed relation, after the upper end of the hanger 10 has been placed therebetween, and combinedly of transverse and vertical dimensions to fit more or less snugly into the socket formed between the upper and the lower jaws and the partial rearwardly curved end walls 13 of the bracket 11, as shown in Figure 1.

The matching or hanger receiving surfaces of each retainer member are provided with an arcuate groove 14 extending longitudinally from end to end to provide a substantially circular channel for the end of the hanger 10 when the members are in superposed relation. The grooves 14 of each member, intermediate the ends, are straight for a given distance beyond each side of the transverse median line of the member and then gradually increase in depth and width toward both ends so as to provide a channel with flaring ends as shown more clearly in Figures 4 and 5, in order to provide sufficient freedom for the hangers and permit the brake beam to move laterally.

With retainers as heretofore employed, having channels of equal cross sectional dimensions, the hangers failed to have sufficient freedom to accommodate for the lateral movement of the brake beam. As a result, the hangers were subjected to considerable strain and the retainers became worn at the ends of the hanger bearing. Furthermore, by reason of the lack of freedom between the rigid hangers and their retaining members, which interfered with proper movement of the brake beam, considerable wear on the outside of the brake head resulted because the wheel flange crowded the shoe, due to the fact that the brake beam with the attached brake head and the shoe did not have sufficient freedom.

My improved retainer is designed to permit the brake beam to float with the wheels, thereby relieving the hanger of lateral strains, eliminating wear between the retainers and the brackets and, preventing the retainer holding pin or key, shown at 15, in Figures 1 and 2, from working loose; while at the same time providing the desired lateral movement of the hanger without permitting undesirable vertical movement of the hanger.

The matching or channeled faces of the retainer members, which are identical in construction, on the inner sides, namely the sides which extend into the rear of the pocket in the bracket 11, are each provided with an upstanding lug 16, preferably with an arcuate forward surface, and

with a socket 17, which preferably also has an arcuate forward surface; while the ends of the retainer beyond the lug and the socket are offset inwardly and provided with arcuate surfaces, as shown at 18, to seat against the arcuate side walls 13 of the bracket, while the intermediate lug and socket containing portion of the inner or rear wall of the retainer enters the bracket pocket between the bracket walls 13 and holds the retainer against lengthwise movement.

The outer or forward side of each retainer member 12, intermediate the ends, has a vertically disposed arcuate groove 19 which is adapted to register with holes in the upper and lower jaws of the bracket 11, for the passage of the retainer holding pin or key 15, which locks the retainer against forward movement out of the bracket pocket.

The forward side of each retainer member 12, at the ends, is offset inwardly and the offset portion at one end provided with an upstanding trunnion providing lug 20, one side whereof is flush with the end of the retainer and the rear wall made arcuate as shown at 21; while the forward or outer side of the lug is provided with a socket 22 which is shown extending throughout the length of the lug 20.

The forward side of the retainer member 12, adjacent the other end, is provided with an upstanding boss 23, formed integral with the forward main wall or side of the retainer member with the rear wall of the boss 23 spaced forward of the inset or recessed end wall portion 24. The boss 23 is formed adjacent the flat matching surface of the retainer member and extends into the plane of the inner arcuate end of the socket 22, and is provided with a substantially semi-circular rear surface as shown at 25 adapted to match or register with the arcuate inner surface of the socket 22 of the complementary or companion retainer member when the two are placed in superposed relation. That is to say, after the brake hanger 10 is placed in the groove 14 of the lower member 12, the upper member 12 is then edgewise rocked or swung on top of the lower member with the upper end of the hanger in the channel. As is apparent, the top member facing downwardly will be reversed end-for-end from the lower member so that the boss 23 of the upper member will be adjacent the socketed lug 20 of the lower member while boss 23 of the lower member will be adjacent lug 20 of the upper member, permitting the boss 23 of both members to enter the sockets of the lugs 20 when the top member is edgewise rocked or tilted onto the lower member. As shown in Figure 2, when the bosses 23 are in their respective sockets, the arcuate rear walls of the lugs 20 will engage the recessed walls 24 at the ends of the two members and thereby guide the top member into proper seating position, at which time the ends of the lugs 20 will overlap the bosses 23 and thereby lock the two retainer members against vertical movement and also against transverse movement, as well as movement longitudinally of each other. The two blocks or retainer members 12 are held against any separating vertical movements that otherwise might result from the upward thrusts of the brake hanger during braking operation and hence eliminates the possibility of the holding pin or key working loose in the bracket. With the two retainer members positioned on each other as described, the lugs 16 of the two members will register with the respective sockets 17 and thus lock the inner or rear sides of the retainer members

against relative transverse and longitudinal shifting movement; the rear longitudinal sides of the members being held in seated relation by the rear walls of the bracket.

5 In order to permit the bosses 23 to enter the sockets 22 of lugs 20, the lugs extend sufficiently above the main intermediate side walls of the retainer members to provide a socket side opening 26 for the passage of the boss connecting base portion 27 of each member, as shown in Figure 2.

As both members of the retainer are similar in construction it is apparent that, in the event the lower member (which receives the greatest wear) becomes worn, the retainer may be removed from the bracket and reversed on the hanger; or either member may be removed without renewing the entire retainer; and while the exemplification is believed to be the best embodiment of my invention, certain structural modifications may be possible without, however, departing from the spirit of my invention as defined in the appended claims.

What I claim is:

25 1. Brake hanger retainers comprising a pair of similar members adapted to be superposed on each other and each provided with a hanger receiving groove extending from end to end and flared toward the ends, the members being provided with vertically off-set complementary surfaces adapted to effect interlocking engagement whereby vertical movement between the members is prevented.

35 2. Brake hanger retainers comprising a pair of similar members adapted to be superposed on each other and each provided with a hanger receiving groove extending from end to end and increasing diametrically toward the ends, each member being provided with a vertically disposed socket forming portion and with a vertically disposed boss portion, the boss portion of one member being adapted to edgewise enter the socket of the other member and thereby effect interlocking engagement against relative vertical movement between the members.

40 3. Brake hanger retainers comprising a pair of similar members provided with brake hanger receiving grooves extending from end to end; each member at one longitudinal side having an upstanding lug provided with a vertically disposed socket open at the sides and closed at the top, and an off-set boss adapted to enter the socket of the other member and thereby effect interlocking engagement between the members against vertical movement between the members.

45 4. Brake hanger retainers comprising a pair of similar members provided with matching faces provided with brake hanger receiving grooves extending from end to end; each member at one longitudinal side having a boss portion and a socket portion adapted to receive the boss portion of the other member to prevent transverse and longitudinal movement between the members, while the other longitudinal side of each member has an upstanding socket providing portion and an off-set boss adapted to enter the socket of the other member and thereby effect interlocking engagement between the members against vertical movement between the members.

50 5. Brake hanger retainers comprising a pair of similar members provided with matching faces provided with brake hanger receiving grooves extending from end to end; each member at one longitudinal side having complementary

surfaces adapted to effect inter-engaging relation with those of the other member to prevent transverse and longitudinal movement between the members, while the other longitudinal side of each member has an upstanding socket providing portion with an arcuate rear face and an off-set boss with an arcuate rear face whereby the members are guided into interlocking engagement with each other and relative vertical movement between the members prevented.

6. Brake hanger retainers comprising a pair of similar members provided with matching faces provided with brake hanger receiving grooves extending from end to end; each member at its ends being transversely reduced and one reduced end provided with an upstanding arcuate lug having a vertically disposed socket in its outer face, while the other end of each member is provided with a vertically disposed off-set arcuate boss spaced outwardly from the adjacent reduced end and adapted to enter the socket of the other member, whereby the members are guided into interlocking engagement against relative vertical movement between the members.

7. Brake hanger retainers, adapted to be inserted in the brake hanger brackets of a car truck, comprising a pair of similar members reduced at their ends and provided with arcuate surfaces adapted to seat against the arcuate side walls of the bracket; said members having matching surfaces to permit the members to be superimposed on each other, said matching surfaces having longitudinally disposed brake hanger receiving grooves increasing in diameter toward their ends; each member at one longitudinal side having complementary surfaces for effecting interengaging relation between the two members against transverse and longitudinal movement, while the other longitudinal side of each member has a socketed upstanding lug and an offset upstanding boss, the lugs and bosses of the two members being formed to guide the members into lug-and-boss interlocking position.

8. Brake hanger retainers comprising a pair of similar members provided with hanger receiving grooves and adapted to be arranged in superimposed relation, both members on one of their longitudinal sides adjacent their upper contacting surfaces having a pair of similar vertically arranged complementary portions whereby the members are guided into groove registering position and said complementary portions are guided into interlocking relation and the two members thereby locked against relative vertical and transverse movements; the longitudinal sides of both members, intermediate said complementary portions having vertically disposed locking pin receiving sockets.

9. Brake hanger retainers comprising a pair of similar elongated members adapted to be arranged in superimposed relation, each member having a longitudinally extending hanger receiving groove, the major portion whereof extends substantially parallel with the brake hanger while the end portions of the groove are flared to permit the brake hanger to be tilted laterally; each member at one of its longitudinal sides having a vertically disposed portion extending above the grooved face of the member and provided with a vertical slot in its outer face terminating beneath the top of said portion and opening through the

side at the upper end of said portion; the same longitudinal side of each member also having a vertically disposed off-set boss portion extending above the grooved face of the member and adapted to seat in the vertical slot of the other member, whereby the two members are locked together against relative vertical movement.

10. Brake hanger retainers comprising a pair of similar members adapted to be arranged in superposed face-to-face relation and formed to provide a brake hanger receiving groove extending from end to end; each member at one longitudinal side, adjacent one end, having a socket closed at its upper end and open at the longitudinal side of the member, each member at the same longitudinal side, adjacent the other end, having an off-set boss adapted to enter the socket of the other member and thereby effect interlocking engagement between the members against vertical displacement.

11. Brake hanger retainers adapted to fit into the open sided socket of a brake hanger bracket comprising a pair of complementary members provided with flat matching faces and adapted to be superposed on each other, each member having a hanger receiving groove extending from end to end and provided at its inner longitudinal side with a socket and an upstanding lug adapted to match the socket of the other member, the members at their outer longitudinal sides adjacent one end having an upstanding socket forming portion open toward the outer side and at the side adjacent the top and an upstanding off-set boss adjacent the other end, the contacting surfaces of said socket and of said boss being arcuate to adapt the members to be edgewise moved into place to effect interlocking engagement between the two members against vertical movement.

12. Brake hanger retainers comprising a pair of members adapted to be superposed on each other, each provided with a hanger receiving groove, the members at their outer longitudinal sides being each provided with similar off-set surfaces consisting of a vertically disposed and closed top socket at one end and an upstanding boss at the other end matching said socket whereby the boss of one member will effect interlocking engagement with the socket of the other member when said members are in superposed relation to prevent relative vertical movement between the members.

13. Brake hanger retainers comprising a pair of similar members adapted to be superposed on each other and each provided with a hanger receiving groove extending from end to end, each member being provided with a socketed portion adjacent one end having an overhanging wall at top arranged above the plane of the main body portion of the member so as to provide a socket open toward the outer longitudinal side of the member and open laterally above the adjacent main body portion and with a vertically disposed boss portion at the other end terminating in a horizontal plane beneath that of said overhanging wall of said socket portion so as to fit into the socket of the other member beneath said overhanging wall to prevent vertical separation of the members, the socketed portion of one member being adapted to edgewise receive the boss portion of the other member and thereby effect interlocking engagement.

MALCOLM S. JOHNSON.
